UNITED STATES PATENT OFFICE:

JEFFERSON D. THOMPSON, OF WASHINGTON, DISTRICT OF COLUMBIA.

SKYLIGHT CONSTRUCTION.

1,004,938.

Specification of Letters Patent.

Patented Oct. 3, 1911.

Application filed September 22, 1910. Serial No. 583,209.

To all whom it may concern:

Be it known that I, JEFFERSON D. THOMPSON, a citizen of the United States, residing at Washington, in the District of Columbia, have invented new and useful Improvements in Skylight Construction, of which the following is a specification.

My invention relates to improvements in skylight construction, and is directed more particularly to the skylight bars or astragals which support the edges of the glass plates of the skylight.

One object of the invention is to provide a novel form of astragal which shall be of simple and economical construction, combined with great strength and lightness, and provided, furthermore, with suitable gutters for carrying away any water that through imperfect construction or otherwise, enters from without between the glass plates and the glass plates and astragal.

Another object of the invention is to provide slightly yielding carriers or supports for the cushion or glazing strips, preferably made of a soft metal, which tend to hold said cushion or glazing strips in firm, close and fluid tight contact with the glass plates.

With these and other objects in view, the invention consists of the novel construction and arrangements of parts hereinafter described and claimed and illustrated in the accompanying drawings, in which—

Figure 1 is a cross sectional view of my improved astragal or skylight support. Fig. 2 is a perspective view of the members of the astragal separated. Fig. 3 is a longitudinal sectional view on the line 3—3 of Fig. 1, and Fig. 4 is a view similar to Fig. 1 showing two glass plates in position thereon and the manner of securing them. Fig. 5 is a side elevation of a section of skylight constructed in accordance with my invention. Fig. 6 is a plan view of one of the cross gutters used with the skylight shown in Fig. 5.

The astragal or skylight bar A is made wholly of sheet metal and in two parts or members, inter-connected and fastened rigidly together by rivets, screws or bolts. The lower part or member 10 of the astragal is made by doubling upon itself, longitudinally and centrally, a sheet of metal to form an upstanding central web 11, the folded sides of the sheet forming said web being in close contact. The fold 11^a of

the sheet being uppermost, at a suitable distance below the same, the aforesaid sides are bent outwardly in opposite directions and in a straight line perpendicular to the web to form flanges 12 having upturned edges 13, the web, flanges and upturned edges forming gutters 14, on each side of the central web 11. The upper part or member 15 is also made of a single sheet of metal bent centrally upon itself to form an open web 16 of sufficient width to receive the web 11 and bear closely against the outer sides thereof, and permanently fastened together by rivets 30. Screws or bolts may be used in some instances if desired. The folded sides of the member 15 are bent outwardly in a curve at 17 and then extend upwardly on opposite sides of and parallel, or nearly so, to the web 16 for a short distance, preferably less than one-half the height of the web 16, to form sides 18 for gutters 19. The upper edge of each side 18 is bent over at 18^a to form a rounded seat or support for a soft metal cushion or glazing strip 20 on which bears a glass plate 21 of the skylight held in place by a cap or crown piece 22 and bolts and nuts 23 as fully described in my application for patent Serial No. 498,631.

Between the fold 11^a of the web 11 and the fold 16^a of the web 16 is a space 24 in which the elongated head 25 of the fastening bolts 23 are held. The shanks of the bolts pass through round holes 26 in the fold 16^a while their heads, fitting snugly between the folds 11^a and 16^a and the walls of the open web 16, hold the shanks of the bolts firmly in an upright position as shown, so that the cap or crown piece 22 can be readily placed in position. The ends of the bolts are pointed to enable them to puncture the cap or crown piece, usually made of copper, when the latter is struck by a mallet.

The cushion or glazing strip 20 is very similar to that described in my application for patent previously mentioned, the vertical walls 27 in the present instance, however, being tapered from the transverse web 28 to the free edges which are very thin and the faces of the web are made concave so as to fit snugly over the bent over edge 18^a of the gutters 19.

It is to be noted that the inner sides of the gutters 19, formed by the web project unbroken some distance above the upper

surfaces of the glass plates, and that the lower gutters 14 extend laterally beyond the cushion or glazing strips 20. Any water, therefore, which could leak under 5 the cap or crown piece 22 would either drop into the gutters 19 or run down the sides of the web 16 into said gutters. If the water ran backward on the under surface of the glass plates, it would run down the 10 inner walls 27 of the glazing strips and the walls 18 into the gutters 19; or if it passed the inner walls 27, it would be caught by the outer walls 27 and run along the channels in said strips, or it would drop down the 15 outer faces of the outer walls into the lower gutters 14. It will thus be seen that no water leaking into the skylight can drop therefrom but will be caught by one or more of the several gutters and be carried off. 20 The shape of the aforesaid gutters 14 and 19 may be changed at pleasure. The former may be semi-circular and the latter angular, or both pairs may be alike.

In the construction of skylights with astragals A formed as hereinabove described, the lower and upper members 10 and 15, respectively, are described as extending continuously and parallel to each other from the ridge to the eaves without interruption, 25 in which case the surfaces of the glass plates will lie substantially in a plane. It is, however, often desirable to overlap the plates of glass, as represented in Fig. 5, after the manner of shingles, in which case, 30 the lower members 10 of the astragals will preferably be made continuous from ridge to eaves, but the upper members 15 will be divided into longitudinal sections 35 equal in number to the horizontal rows of glass 35 plates on the side of the skylight. Each section 35 is fastened by rivets 30 or screws to the member 10 as previously described, but the sections are inclined with relation to said member, the lower end of each section being higher than the upper end and overlapping the next lower section so that water, should any enter between the sections, will be quickly and safely carried off.

Supported on the soft metal cushions or 50 glazing strips 20 of each pair of laterally disposed sections 35 is a plate of glass 21, the lower end of each plate overlapping the plate next below it a sufficient distance to prevent water, under ordinary circumstances, entering between them. To further insure against the entrance of water, the overlapping portions of the plates are slightly separated for the insertion of a corrugated strip 36 of soft material as lead, 55 the elevations and depressions of which bear on the proximate surfaces of the two plates, and being soft, this corrugated strip readily yields to any inequalities in the surfaces of said plates. The corrugated 60 strip is readily retained in place by fold-

ing down its upper edge 37 over the upper edge of the lower plate of glass as shown in Fig. 5.

Extending transversely between each pair of astragals A below the overlapping edges of the glass plates 21 are placed cross gutters 38. These gutters 38, in this form of the invention, are each made, preferably, of sheet metal and are carried at their ends on the upturned edges 13 of the gutters 14 and empty into them, see Fig. 4. Each end of the transverse gutters 38 has a downward turned lip 39, as shown, to prevent water from running backwardly on the bottom of the gutters 38 and escaping over the edges of the gutters 14. The transverse gutters 38 are provided each with a flange or lip 40 on its downward side 41 which lip bears on the under side of the upper end of a glass plate, and from the opposite side 42 of each of said gutters, a short distance below the glass, extends a plate 43 beyond the end of said glass where it is turned up to form a flange 44. The metal plate 43 is formed with upwardly projecting ribs 45 on which the upper end of the aforesaid glass plate rests, thus providing a space between the glass and the metal plate 43 for the circulation of air. The upturned flanges 44 prevent all moisture which from faulty construction or imperfections in the glass plates or corrugated lead strips 36, enters between the overlapped plates of glass from escaping over the edges of said plates 43 and compels it to run down said plates into the gutters 38. The ends 46 of the plates 43 project beyond the ends of the cross gutters 38 and rest on the glazing strips 20, see Fig. 6.

From the above, it will be noted that the glass plates 21 are not only supported on their side edges by the glazing strips 20, but are carried at their ends by the transverse gutters also, thus giving strong and perfect support to each glass plate and providing absolutely leakless joints. The cap or crown piece 22 in this type of skylight is also made in sections, each section tapering outwardly from above downwardly so that the top 22 of each crown piece section will be close to the fold 16^a of the upper sectional member 16 where it is fastened, and the soft lead packing strips 47 on the lower edges will lie in close contact with the glass plates 21.

The soft metal glazing strips 20 are not permanently attached to the members 15, but are placed in position thereon only after the astragals and other framing are finally secured in place ready for the glass. The glazing strips are then carefully placed in position and the lower walls 27 dressed firmly against the sides 18 of the gutters 19. The pressure on the glazing strips is always downward so there is no danger of displacement, while, if through some cause it be-

comes necessary to renew a strip, this can be quickly done by removing the necessary crown pieces and glass. Furthermore, by not fastening the glazing strips permanently 5 on the astragals, there is no danger of marring the relatively sharp edges of their walls, either when shipping, or when erecting the structure, and thus water tight joints are the rule and not the exception.

10. What I claim is:—

1. An astragal for skylights comprising an upper and a lower member each made of resilient sheet metal with a central web and a gutter on each side of the same, said 15 webs being interconnected, the gutters of the upper member forming yielding supports for the glass plates of the skylight, and movable cushioning or glazing strips carried on the outer edges of said gutters.

2. An astragal for skylights comprising an upper member and a lower member, each member being made of a single sheet of metal bent to form a central web and a gutter on each side of each web, the web of one 25 member fitting into the web of the other member and the gutters of one member being spaced from and vertically above the gutters of the other member, and means for fastening said members together through 30 the webs.

3. An astragal for skylights made wholly of sheet metal comprising two members, each consisting of a strip of resilient sheet metal bent intermediate its edges to provide a central web, the web of one member being open to receive the web of the other member, and the free longitudinal edges of said members being bent outwardly and upwardly to provide upper and lower gutters 35 on each side of the central webs, said gutters lying beneath the glass plates of the skylight and the uppermost gutters forming yielding supports for said glass plates.

4. An astragal for skylights made wholly of sheet metal comprising two members, each consisting of a sheet of somewhat resilient metal bent to form a central web, the web of one member fitting snugly within the web of the other member and the free 45 longitudinal edges of said members being bent outwardly and upwardly to provide upper and lower gutters on each side of the central webs, and return bends on the outer edges of the upper gutters to form yielding 50 supports for the glass sheets of the skylight, and removable soft metal glazing strips adapted to straddle said return bends.

5. An astragal for skylights made wholly of somewhat resilient sheet metal bent into 55 shape and comprising separately formed upper and lower members having inter-engaging webs, and gutters on each side of said webs, the outer edges of the gutters on the upper member being arranged for 60 glazing strips, and glazing strips removably

applied to the said outer edges of the gutters formed on the upper member, the gutters of the lower member being lower and projecting beyond the gutters of the upper member, fastening devices extending through 65 the webs of both members.

6. An astragal for skylights made wholly of sheet metal comprising two members, each consisting of a strip of resilient sheet metal bent intermediate its edges to provide a central web, the web of one member fitting snugly within the web of the other member, the free longitudinal edges of said members being bent outwardly and upwardly to provide upper and lower gutters on each side 70 of the central webs, the lower gutters extending laterally beyond the upper gutters, and the upper gutters forming yielding supports for the glass plates of the skylight, and cushioning or glazing strips between 75 the yielding edges of the gutters and said glass plates.

7. An astragal for skylights made wholly of sheet metal comprising two members each consisting of a strip of sheet metal bent intermediate its edges to provide a central web, the web of one member fitting snugly within the web of the other member, a space being left between the folds forming the tops of said webs, a bolt projecting through 80 the fold of the upper web with its head secured in said space, and upper and lower gutters formed by bending the free sides of each member outwardly and upwardly.

8. An astragal for skylights comprising a 100 continuous lower member and a sectional upper member having interconnected central webs and gutters on each side of said webs, each section of said upper member overlapping the section below and inclined 105 relatively to the lower member, yielding glazing strips carried on the gutters of each section to support a glass plate and conform to any irregularities therein, and a crown piece made of overlapping sections, each 110 section adapted to bear on and hold a sheet of glass in position.

9. An astragal for skylights comprising a continuous straight lower member and a sectional upper member having interconnected central webs and gutters on each side of said webs, each section of said upper member overlapping the section below and inclined relatively to the lower member, cross gutters, their ends resting on the gutters of both members and provided with means for supporting the ends of plates of glass, soft metal glazing strips carried on the gutters of each section to support the sides of said glass plates, a crown piece 115 made in overlapping sections, adapted to hold the plates of glass in position, and means for fastening said sections to the aforesaid interconnected central webs.

10. A skylight comprising a plurality of 130

astragals each made of a continuous lower member and an upper member formed of overlapping sections, each section inclined relatively to the lower member, longitudinal gutters on the sides of the lower members and each section of the upper members, a plurality of cross gutters extending between each pair of astragals, glass plates supported on the outer edges of the gutters of said sections and on the cross gutters, each glass plate overlapping the upper end of the plate next below, a corrugated soft filling strip between said overlapping ends of the glass plates, soft metal cushion strips on the outer edges of said gutters of the upper member sections, and overlapping sectional crown pieces for holding the glass plates in position.

11. A skylight comprising a plurality of 20 astragals each made of a straight continuous lower member and an upper member formed of straight overlapping sections, each section inclined relatively to said lower member, longitudinal gutters on the sides of 25 the lower members and on each section of the upper members overlapping the similar gutter next below, soft metal cushion strips on the outer edges of said section gutters, glass plates supported on said cushion strips, 30 each plate overlapping the plate next below, corrugated filling strips of soft material between said overlapped ends of the

glass plates, and overlapping sectional crown pieces adapted to hold said glass plates in position on said cushion strips. 35

12. A skylight comprising a plurality of astragals each made of a continuous straight lower member and an upper member formed of straight overlapping sections, each section inclined relatively to said lower member, longitudinal gutters on the sides of the lower members and on each section of the upper members, cross gutters between said astragals supported at their ends on said longitudinal gutters and opening into 40 those of the lower members, said cross gutters each having an outwardly extending plate on one side provided with upstanding ribs and a lip on its opposite side, cushion strips on the gutters of each section, 45 overlapping glass plates supported on said cushion strips, ribs and lips, a filling strip of soft material between the overlapping ends of the glass plates, and sectional crown pieces for holding the glass plates in position. 50

In testimony whereof I have hereunto set my hand in presence of two subscribing witnesses.
